UNITED STATES PATENT OFFICE

JOHN JOHANNESSEN, OF NEW YORK, N. Y.

GAME BOARD

Application filed September 25, 1928. Serial No. 308,176.

This invention relates to a new and useful sociable play or game, and has for one of its objects to provide an interesting and wholesome entertainment which may be participated in by older and younger people alike, and played by several at the same time.

With the above object in view, it is a still further purpose to provide a medium in the form of a play, as here exemplified by an illustrated card-board, which from a traveling point of view should convey to the youthful player a thrill of adventure and thereby contribute to his general interest in educational subjects, besides incidentally adding to his mental development through the constructive thinking, necessary to play the said game and observe the technical rules associated therewith.

The device or play comprises a number of sections subdivided into a plurality of disc-formed spaces some of which are subject to be covered in turn through different advancing motions as the game progresses, and the player endeavors to reach his coveted destination the Eiffel Tower in Paris. It will be noticed that several pictures imitating clouds have in this play, like in the actual field of aviation a fatal influence upon the advance of the traveling or moving plane or pawn in the game as the said clouds by the rules of the latter compel the imaginary flyer to discontinue his trip, and either return or descend.

In order to lend an atmosphere of reality to this play, the pawns may be constructed with a top simulating to some extent an airplane.

As this device is comparatively simple of construction and may be made from inexpensive material the manufacturing cost thereof should accordingly be small; it is further thought that the demand for this article should be very great as the idea embodied therein embraces and typifies the greatest topic of the day.

With the above and other objects in view, this invention consists of the novel features of construction, combination and arrangements of parts, hereinafter fully described, claimed, and illustrated in the accompanying

drawings forming parts of this specification, and in which similar characters of reference indicate corresponding parts in all views, and in which Figure 1 is a plan view of my device.

Referring in detail to the drawing 10 indicates four preferably corner sections, incidentally permitting four players to participate in the game. It will be noticed, that the said sections 10, each comprises substantially an equilateral parallelogram shaped as a rhombus.

The said sections 10 are crosslined in a manner, as shown, in part, by the lines 11 and 12, whereby further a plurality of small parallelograms are formed, the latter in turn being crossed respectively by a number of parallel lines joining the farthest points of said parallelograms. Along the latter lines, and especially where these are cutting the aforesaid crosslines, are disposed a number of disc-formed areas, indicating the relative positions the pawns may assume during an advancing movement as the game proceeds. It will be further observed that whenever a pawn moves it will have to follow one of the lines radiating, usually in a flaring manner, from its last position. It will thus be seen that in most cases, when a pawn is moving, it will have the choice of one of three roads or lines along which to move forward in order to reach the goal indicated by the Eiffel Tower.

The movements of the said pawn, indicated by 13, is controlled by the result derived from the action of dice-playing, the number of dice employed for this purpose being optional with the players, who throw the said dice in turn and consequently move their respective pawns forward according to the numeral indicated upon the dice, the usual rules being followed. While there, as stated before, normally would be a certain latitude in regard to, in which direction to move, as there usually are three lanes to choose from, as exemplified by 14, 15, and 16 relative to 6 as a starting point, it must, however, be remembered, that if by choosing any lane, which eventually by continued movements leads to the outskirts of the rhombus, where the clouds 17 are located, the player will be defeated in his purpose,

that is, be prevented by the said cloud from any further advance with the result, that if he reaches the spot indicated by 18, he will have to go down upon the sea to be picked up by the ship 19, or if he reaches the spot 20 he must retrace his step as indicated by the dotted line 21, which in reality merely means, that he must start his part of the game anew.

In playing this game the participants naturally start from the bottom, or the corner, where a single disc-formed area indicated by 6' is shown. It will be quite evident that unless a dice showing the numbers 4, 6 or 5 is thrown, the first move is frustrated, and the player will await his next turn before he tries again to get one of the said numbers, which would start him moving into the next line; once advancing that far the scope of possibilities widens as the player gets nearer to his goal, being from now on able to utilize a greater amount of numbers displayed by the dice. Several pawns may be used as well as several sets of dice, according to the choice of the players. In like manner it is evident, that slight modifications may be made in the rules governing the advancement of the pawns. Objects serving imaginary purposes have been introduced, and with the rules imitating those governing the actual life brought to play a part in this game, it is thought that the latter should be received by the public in a spirit of more than usual interest.

It is obvious that changes may be made in the form construction and arrangement of the several parts, as shown, within the scope of the appended claims, without departing from the spirit of the invention, and I do not therefore limit myself to the construction and arrangement shown and described herein.

49. What I claim as new, and desire to secure by Letters Patent of the United States, is:

1. A game consisting of a game board having four rhomboidal sections arranged in star-like manner, parallel and cross-parallel lines dividing each of said sections into a plurality of similar rhomboidal spaces, circular areas carrying numerals at the junctures of said lines, pawns adapted to be placed on said areas and to be moved along said lines, a goal, indicated by a picture, arranged in the center of the board between said star-like sections, diagonal central lines passing through said rhomboidal sections and converging at said goal and forming the only pathway for the pawns to reach said goal, and chance means regulating the movement of said pawns.

2. A game consisting of a game board having a plurality of substantially congruent sections arranged in a star-like manner, parallel and cross-parallel lines dividing each of the said sections into a plurality of similar congruent spaces, circular areas carrying numerals at the junctures of said lines, pawns adapted to be placed on said areas and to be

moved along said lines, a goal, indicated by a picture, arranged in the center of the board between said star-like sections, diagonal central lines passing through said congruent sections and converging at said goal and forming the only pathway for the pawns to reach said goal, and chance means regulating the movement of said pawns, substantially as shown and described.

Signed at New York city, in the county of New York and State of New York, this 7th day of September A. D., 1928.

JOHN JOHANNESSEN.
